UNITED STATES PATENT OFFICE.

CARL DOERING, SR., OF CHICAGO, ILLINOIS.

ADJUSTABLE DISPLAY-RACK.

1,035,553.

Specification of Letters Patent. Patented Aug. 13, 1912.

Application filed November 16, 1911. Serial No. 660,556.

To all whom it may concern:

Be it known that I, CARL DOERING, Sr., a citizen of the United States, and residing at Chicago, in the county of Cook and State of Illinois, have invented a new and useful Improvement in Adjustable Display-Racks, of which the following is a complete specification.

The main objects of this invention are to 10 provide an improved display rack; to provide a display rack in which the sizes of the compartments may be readily adjustable; and to provide a display rack of cheap, simple and strong construction having im- 15 proved means for securing the partitions in place.

The invention consists of matters herein- 20 after described in the specification and more fully pointed out and defined in the ap- pended claims.

In the drawings: Figure 1 is a front elevation of a display rack embodied in this invention. Fig. 2 is a vertical transverse section of the rack. Fig. 3 is an enlarged 25 fragmentary perspective view of the rack with the end member removed. Fig. 4 is an enlarged fragmentary perspective view of a modified form of the rack.

As shown in the drawings: Referring 30 first to Figs. 1 to 3 inclusive, a frame is provided which comprises a relatively high back member 1, a relatively low front member 2, and downwardly and forwardly sloping or inclined end members 3, all of which 35 are preferably formed of sheet metal or other light, strong and rigid materials.

Secured to the back and end members are the shelves 4 which are arranged stair-wise, that is each succeeding one from the front 40 being above and to the rear of the preceding one.

Extending along the inner side of the back and front members, at the top thereof, are the corrugated partition supports 5 and 45 6, which are preferably formed of separate strips of metal attached to said front and rear members, though said members may themselves be corrugated to provide the supports if desired.

50 The partitions 7 extend from the front to the rear of the rack, with their ends projecting into said corrugations which act to hold the partitions in an upright position. The partitions rest on their lower edges on the 55 front edges of the shelves 4, and each partition is preferably formed of a strip of sheet

metal folded longitudinally upon itself to provide a double thickness, and at a point above the front edge of each shelf a pair of ears 8 are turned oppositely from the sides 60 of the partition and rest on the tops of the shelves. Said ears extend vertically and act to hold the cards or other articles in the compartments formed by the partitions and shelves. The side or end members 3 are 65 likewise provided with inturned ears 9 which serve the same purpose as the ears 8.

For the purpose of holding the partitions in place a locking bar 10 is secured to the top of the back member 1 and has a for- 70 wardly projecting flange 11 which overlaps the upper ends of the partitions. Said bar and back member are provided with register- 75 apertures in which are secured locking clips 12 which hold the bar in place. Said bar is preferably formed of a strip of metal bent longitudinally to form a loop which hangs over the top of the back mem- 80 ber, and from the lower edge of which projects the flange.

In the construction shown in Fig. 4 the back member 13 does not extend below the upper shelf, and the end members 14 are relatively narrow. Hinged to the back mem- 85 ber 13 by means of clips 15 are legs 16 which are adapted to extend downwardly and rear- 90 wardly from the back member to support the frame. A rod or locking bar 17 extends through the upper ends of the end members in position to overlap the upper ends of the 90 partitions.

The operation of the construction shown is as follows: The partitions are adjusted to provide compartments of the desired width, and when the locking bar is secured in place 95 the partitions are rigidly held in position. The cards or other articles placed in the compartments are prevented from falling forwardly by the ears 8 and 9, and they are fully exposed to view.

Obviously many details of the construction shown may be varied or omitted without departing from the scope of the claims.

I claim:

1. A display rack comprising a frame, shelves arranged stairwise in the frame, partitions extending from front to rear trans- 105 versely of the stairs, corrugated members at front and rear adapted to receive the ends of the partitions, and an L-shaped locking 110 bar, one arm of said bar being formed of a strip of metal bent longitudinally to form a

loop, said loop being adapted to hang over the back of the frame, the other arm of said bar being adapted to project over one of said corrugated members.

5. 2. A display rack comprising a frame, shelves arranged stairwise in the frame, partitions extending from front to rear transversely of the stairs, corrugated members at front and rear adapted to receive the 10 ends of the partitions, an L-shaped locking bar, one arm of which engages the back of the frame, there being perforations in said locking bar and the back, and clips adapted to pass through said perforations and retain 15 said locking-bar in place.
3. A display rack comprising a frame, shelves arranged stair-wise in said frame,

partitions extending from front to rear transversely of the stairs, corrugated members at front and rear adapted to receive the 20 ends of the partition, the ends of said frame being perforated, and a locking bar extending from one side of the frame to the other and through said perforations, and being disposed above said partitions, said locking 25 bar being provided with a screw-threaded end and a nut exterior of said frame.

In testimony whereof I have hereunto subscribed my name in the presence of two witnesses.

CARL DOERING, SR.
